KNITTING MACHINE WITH INTERCHANGEABLE NEEDLE CARRIERS

Walter Larkin, Norristown, Pa., assignor to
Fidelity Machine Company, Wilmington, Del.,
a corporation of Delaware

Application April 26, 1939, Serial No. 270,242

11 Claims. (Cl. 66—115)

This invention relates to knitting machine and more especially to the circular type adapted for knitting tubes of extremely small diameters, such for example, as those employed in insulating electric wires or for knitting reinforcing fabrics in the manufacture of rubber hose. Machines of the type to which the present invention is particularly adaptable are clearly shown in my prior U. S. Patents No. 2,032,993, dated March 3, 1936, and No. 2,084,770, dated June 22, 1937.

In machines of such small knitting diameters the cam rings have been correspondingly small in diameter, and in order to provide the necessary amount of longitudinal movement for the needles in the knitting cylinder, relative to the knitting point, the angle of the inclines of the needle raising and lowering cams have necessarily been so steep as to preclude running of the machines at high speeds.

Furthermore, the sharp inclines of the needle operating cams have caused excessive wear in the walls of the needle slots of the needle cylinders, and excessive wear on the edges of the needle butts engaged by the cams. Also, the relation of the cam inclines to the butts of the needles frequently causes the butts to become broken, requiring replacement of the broken needles which, in machines of the type noted, is a time consuming operation.

The primary object of the present invention is to provide a needle carrier for knitting machines, which shall have an independent and readily detachable and interchangeable support and guide for each needle in the machine, whereby changing of broken or worn needles, or replacement in the carrier of the individual needle guide-supports for any which may develop excessive wear, or replacing the needles operating in the machine with needles of a different gage can be readily accomplished without removing the carrier which takes the place of the conventional needle cylinder.

Another object of the invention is to construct the needle carrier in such a manner as to provide for use of operating cams of relatively large diameters, whereby the needle activating inclines may be made at easy angles, permitting the machine to be operated at relatively high speeds and at the same time reducing breakage of the needle butts and excessive wear on the butts, the walls of the needle guide grooves, and on the operating surfaces of the cams which engage the needle butts.

In the accompanying drawings:

Fig. 1 is a vertical sectional elevation through

a machine of the type shown in the prior Patent No. 2,032,993, with the improved construction of the present invention incorporated therein, this machine being of the stationary cylinder type and employing rotating needle operating cams;

Fig. 2 is a side elevation partly in section of a machine of the type shown in the prior Patent No. 2,084,770, also of the rotary cam type, with the improvement according to the present invention, incorporated therein;

Fig. 3 is an enlarged vertical sectional elevation of the needle carrier and operating mechanism shown in Fig. 2;

Fig. 4 is a detached perspective view of the needle carrier shown in Fig. 3;

Fig. 5 is a detached perspective view of one of the individual needle guide supports of Fig. 3;

Fig. 6 is a fragmentary sectional perspective view of one end of the needle carrier shown in Fig. 4;

Fig. 7 is a vertical sectional elevation of a machine employing a stationary cam ring and a rotating needle carrier with the improvement of the present invention incorporated therein;

Fig. 8 is a sectional plan view taken on the line 8—8, Fig. 7;

Fig. 9 is a sectional plan view taken on the line 9—9, Fig. 7;

Fig. 10 is a detached perspective view partly in section of the needle carrier shown in Fig. 7;

Fig. 11 is a detached perspective view of one of the individual needle guide-supports shown in Fig. 7;

Fig. 12 is a view similar to Fig. 11 showing a modified form of needle carrier guide-support;

Fig. 13 is a fragmentary sectional plan view of the guide-support shown in Fig. 12 applied to a needle carrier suitably modified to receive the same.

As shown in Fig. 1, the machine comprises a base 1 having a circular recess 2 provided with an inturned flange 3 on which is secured, by screws 4, a ring 5. The ring 5 is provided with an inturned flange 6 having a central bore 7 in which is mounted, for rotation between a pair of rings 8 and 9, a flange 10 of a sleeve 11. The sleeve 11 adjustably supports a central hollow tube 12. The ring 8 is secured to the flange 6 by screws 13 and the ring 9 is secured to the flange 6 by screws 14. The sleeve 11 is threaded internally for cooperation with external threads on the exterior of the tube 12, whereby rotation of the sleeve 11 will effect axial adjustment of said tube. Rotation of the tube 12 is prevented by

keys or splines 15 formed on the ring 8 and disposed in longitudinal slots or splines 16 formed in the outer surface of the tube 12. Rotation of the sleeve 11, for effecting adjustment of the tube 12, is accomplished by means of a hand wheel 17 formed on or secured to the lower end of the sleeve 11, below the flange 3 of the base 1. A locking wheel 18 is threaded onto the tube 12 below the sleeve 11, for jamming against the lower end of the sleeve 11 after adjustment of the tube 12 has been accomplished to lock the tube in its adjusted position.

Rotatably mounted in the cavity 2, outside the ring 5, is a gear 20. This gear is secured, by screws 21, to a circular plate 22 which is supported by and on the upper surface of the ring 5 for rotation by the gear 20. Vertical movement upwardly of the plate 22 and gear 20 is prevented by a ring 23, which overlies the peripheral edge 20 of the gear 20 and is secured to the base 1 in any suitable manner. A supplementary plate 24 overlies the ring 8 and is secured to the plate 22 by screws 25, for rotation therewith. The plate 24 supports a cam sleeve 26 which is disposed outside 25 and rotates about the fixed inner tube 12.

Encircling the cam sleeve 26 is the improved needle carrier 30 of the present invention. The needle carrier 30 is provided with a head 29 at its upper end, which overlies the upper end of 30 the cam sleeve 26 and is supported by an annular flange 28 on the tube 12, to which said head is secured by screws 27. Thus the carrier 30 is held against rotation while the cam sleeve 26 is permitted to revolve between the fixed tube 35 12 and the fixed carrier 30. The carrier 30 is provided with a series of longitudinally extending laterally spaced parallel slots 31, one for each needle in the machine. In each slot 31 is an individual needle support 32, which is provided 40 in its inner surface with a longitudinal needle guide groove 33 for slidably supporting and guiding the shank 34 of one of the needles 35.

As shown in Fig. 1, the needles 35 may be divided into two groups, the one group having long shanks 34 while the second group are provided with relatively short shanks 36. The shanks 34 are provided with butts 37 operating in a lower cam groove 38 formed in the periphery of the cam sleeve 26. The shanks 36 of the short needles are provided with butts 39 which operate 45 in a cam groove 40 formed in the upper portion of the periphery of the cam sleeve 26. However, the needles may all be of either the long or short shank type with their butts operating in a single cam groove, if desired.

The inner edges 41 of the needle supports 32 bear against the base surfaces 42 of the portions of the slots 31 formed in the needle carrier 30 which are disposed adjacent the head 29, and against the outer peripheral surface 43 of the cam sleeve 26.

The needle carrier 30 is provided with upper and lower annular grooves 44 and 45 respectively, for reception of split clamping rings 46 and 47 respectively which encircle the carrier 30 and bear against the outer edges 48 of each and all of the needle supports 32, to retain said supports against radial movement outward.

The outer edge of each needle support 32 is 70 provided with a transverse groove 49 adjacent one of its ends for reception of an internal rib 50 formed on the split ring 47, by which longitudinal movement of the needle supports 32, relative to the carrier 30, is prevented.

75 The two halves of the split rings 46 and 47

are pivotally connected by a pivot pin 51 at one side of the carrier 30 and the free ends of said ring-halves are secured together at the opposite side of the needle carrier by screws 52 passing through suitable openings 53 in the one half and 5 threaded into tapped openings 54 in the other half, as clearly shown in Fig. 9.

Above the flange 28, the tube 12 is provided with an annular enlargement 55. This enlargement is provided with longitudinal grooves 56 10 for reception of the upper ends 57 of the needles 35, said needles each being provided with an offset portion 58 compensating for the difference in diameter between the circle on which the upper portions 57 of said needles are located, and the 15 circle on which the shanks 34-36 are located.

The knitting of the fabric x , by vertical or longitudinal movement of the needles 35 in conjunction with feeding a knitting thread thereto, through one or the other or both of a pair of 20 thread guides 59 and 60, takes place between the upper edge 61 of the work tube 12 and the lower edge 62 of a hold-down ring 63.

The hold-down ring 63 is of substantially the same diameter as the tube 12 and is provided on 25 its outer periphery with an annular enlargement 64 in which is provided a series of grooves 65 for receiving the hook ends 66 of the needles 35, the slots or grooves 65 being in alignment with the slots or grooves 56 in the enlargement 55 of 30 the tube 12.

The thread guides 59 and 60 are supported by 35 posts 67 and 68 which are carried by the rotating plate 22 in diametrically opposite relation to each other. These posts also support thread tensioning means 69, 69, one for each of the guides 59 and 60; and a bridge piece 70 which supports an annular abutment 71. The abutment 71 is concentric with the floating hold-down ring 63 and bears against the upper edge thereof to prevent rising of the said floating ring as the fabric x tends to rise during the vertical knitting movements of the needles 35.

As a matter of convenience, the cam grooves 38 and 40 may be formed in or between removable rings or segmental plates 72, which are secured to the cam sleeve 26 to form the outer peripheral surface thereof with the cam grooves therein.

With the mechanism above described, it will 50 be clear that replacement of needles may be readily accomplished by removing the upper split ring 46 and swinging outwardly the needle support 32 of the needle which is to be replaced, using the rib 50 of the lower split ring 47 and the cross 55 groove 49 of the needle support as a fulcrum, the lower inner corner of each needle support being beveled, as indicated at 73 in Fig. 1, to provide clearance for such outward swinging movement of the upper end of the needle support. A 60 new support, or the same support with a new needle therein, may be readily replaced by reversing the operation just described.

It will also be clear that such removal and replacement is made possible by arranging the 65 needles to operate outside the operating cams, instead of inside the operating cams, as is the usual custom, which permits the making of the cams to a larger diameter than has been the custom heretofore, whereby the inclines on the butt 70 engaging surfaces of the cams may be made at easier angles, i. e. inclines of smaller angles, relative to the horizontal, than is possible with the smaller diameter cams.

In the machine shown in Fig. 1, the knitted 75

tube moves downwardly in the direction of the arrow *a* in said figure, through the tube *12* from the knitting line *61*, whereas in the device shown in Fig. 3 the knitted fabric *x* moves upwardly through the tube *12a* from the knitting line *61a*. In each instance, a core element *y* such as an electric wire or cable or a length of rubber tubing etc. is led into the tube *12* or *12a* and past the knitting line *61* or *61a*, through a tube *75* or *75a* which is in axial alignment with the tube *12* or *12a* respectively.

In the structure shown in Fig. 1, the guide tube *75* is supported by the bridge piece *70*. In the structure shown in Fig. 2, the guide tube *75a* forms an extension of a short tube *16*. The short tube *16* is provided with an annular enlargement *17* which is seated in the cavity *2a*, in the frame *1a*, and secured to the flange *3a* by screws *78*. The driving gear *20a*, in this instance, is seated in the cavity *2a* around the outside of the enlargement *17* and carries a rotary plate *22a* which supports the posts *67a* and *68a*. The posts *67a* and *68a* support a ring *79* in which is seated and secured the flange *80* of a cam sleeve *26a*, said cam sleeve being adapted to revolve about the tube *12a* which extends vertically therethrough and is secured by screws *81* to an axially aligned complementary tube *82*.

The tube *82* is surrounded; above the upper ends of the posts *67a* and *68a*, with a collar *83* of the split type which is adapted to be clamped tightly to the tube *82* by a screw *84*. The collar *83* is provided with a bore *88* in which is secured one end of an L-shaped anchorage element *89*, the opposite end of which is secured in a fixed bridge element *90* by which rotation of the tube *82*—*12a* is prevented. The bridge element *90* is supported from the frame work *1a* outside a path of rotation of the elements carried by the rotary plate *22a*, as disclosed in prior Patent No. 2,084,770. The tube *12a* is provided with an annular flange *28a* which is secured, by screws *27a*, to the head *29a* of the needle carrier *30a*, whereby rotation of said carrier is prevented. The upper end of the tube *82* is provided with an annular groove *85* into which extends the head *86* of an adjusting screw *87* which is tapped into the collar *83* and by which axial adjustment of the tube *12a*, through the complementary tube *82*, may be accomplished.

The carrier *30a* is provided with longitudinal slots *31a* in which are mounted the individual needle supports *32a*. In this instance, each support *32a* is provided with a longitudinal projection *91* at one end, which hooks behind the inner surface *92* of the carrier *30a*, at the upper end of the support receiving slot *31a*, and acts as a fulcrum in removing the supports *32a* from the carrier *30a*, as clearly shown at the left in Fig. 3. In this case, each of the supports *32a* is provided with a cross groove *93*, formed in its inner surface, for receiving an outwardly projecting annular extension *94* of the flange *28a*, by which the supports *32a* are maintained in their slots *31a* against relative longitudinal movement with respect thereto.

Radial outward movement of the supports *32a* is normally prevented by a sleeve *95* which embraces the needle carrier *30a*, over substantially the full length and circumference thereof, and rests on an outwardly extending annular flange *96* formed on the lower edge of the carrier *30a*.

The sleeve *95* is provided with a longitudinal slot *97* (see Figs. 2 and 3) which may be brought selectively into alignment with any one of the

needle support receiving slots *31a*, as shown in Fig. 3, to permit outward swinging movement of the needle support *32a*, as shown in said figure. During normal operation of the machine the slot *97* is disposed in line with one of the solid portions *98* of the carrier *30a* (see Fig. 4) disposed between each two of the slots *31a* in which the needle supports *32a* are mounted.

In this instance, the needles *35a* are all of the same length and provided with butts *37a* operating in a single cam slot *38a* formed in the peripheral surface of the cam sleeve *26a*.

In that form of the invention shown in Figs. 7 to 11, the cam sleeve *26b* remains stationary while the needle carrier *30b* revolves about said cam sleeve. The cam sleeve *26b* is provided with a tubular axial extension *99* which is slidably mounted in a bearing *100* formed in the base structure *1b*, said extension *99* having a key *101* secured therein which is adapted to slide longitudinally in a key slot *102* formed in the inner surface of the bearing *100*, as shown in Figs. 7 and 8.

The lower end of the extension *99* is threaded, as indicated at *103*, for reception of an internally threaded adjusting ring *104* which bears against the lower end *105* of the bearing *100* and is retained in contact therewith by a screw *106* which is threaded into a bore *107* formed on the bearing *100*, the head of the screw *106* bearing against the underside of the ring *104* and holding the upper side of said ring in contact with the end *105* of the bearing *100*. Rotation of the ring *104* will effect axial movement of the extension *99* and the cam sleeve *26b*, while the key *101* and key slot *102* prevent rotation thereof.

Rigidity of the cam element *26b* is further provided by a pair of clamp pieces *108* and *109* which are mounted in a transverse bore *110* formed in a lateral extension *111* of the bearing *100* and through which extends a bolt *112* for clamping concaved surfaces *113*, *113*, of the elements *108* and *109* respectively, against the outer surface of the extension *99*, as clearly shown in Fig. 8.

Rotatably mounted in the cavity *2b* of the base *1b* is a driving gear *20b*, which is secured by the screws *21b* to the lower end of the needle carrier *30b*, the upper end of said carrier being provided with a head *29b* secured by screws *27b* to a flange *28b* of the work tube *12b*. Vertical movement of the carrier *30b* is prevented by a hold-down-ring *23b* which is secured to the rigid framework of the machine in any suitable manner.

Carried by the head *29b* is a ring *94b* which extends outwardly beyond the inner surfaces *42b* of the slots *31b* in which the needle supports *32b* are mounted, the outer edge of said ring entering transverse slots or grooves *93b* formed in the inner surfaces of the supports *32b*, whereby longitudinal movement of the supports relative to the carrier *30b* is prevented.

Radial movement of the upper ends of the supports *32b*, outwardly, is prevented by a split ring *46b* which corresponds to the split ring *46* previously noted. Outward radial movement of the lower ends of the supports is prevented by a split ring *47b* corresponding in structure and function to the split ring *47*, previously described. Here again the needles *35b* are of long and short varieties with the butts thereof operating in separate cam grooves *38b* and *40b* in the cam element *26b* in the manner previously described.

If desired, needle supports *32c* shown in Figs. 12 and 13 may be provided with longitudinal

ribs or lateral flanges 115 fitting in corresponding rabbets 116 formed at the opposite sides respectively of the slots 31c, in which the supports 32c are mounted, for preventing inward movement of 5 the supports 32c.

While the invention has been described as being applied to circular knitting machines of small knitting diameters, obviously the principle of the individual supports for the needles mounted for 10 ready detachability in a carrier therefor may be applied to other types of circular machines and under certain circumstances the same principle may be applied to flat bed knitting machines.

I claim:

15. 1. A needle carrier for a knitting machine, a series of separate needle supports detachably carried thereby in laterally spaced parallel relation to each other and respectively mounted in correspondingly laterally spaced parallel slots formed 20 in said carrier, each support including a longitudinal rib along at least one of its side edges adapted to engage the carrier along a corresponding edge of the slot in which the carrier is mounted and functioning as means for preventing 25 movement of the support in one direction perpendicular to the wall of the carrier in which said slots are formed, and readily releasable means for maintaining said supports against perpendicular movement in the opposite direction 30 in said carrier slots.

2. A needle carrier for a knitting machine, a series of separate needle supports detachably carried thereby in laterally spaced parallel relation to each other and respectively mounted in correspondingly laterally spaced parallel slots formed in said carriers, each support including a longitudinal rib along each of its side edges adapted to fit within rabbets formed in the opposite sides respectively of the slots in which the 35 supports are respectively mounted, said ribs and rabbets functioning as means for preventing movement of the support in one direction perpendicular to the wall of the carrier in which said slots are formed, and readily releasable 40 means for maintaining said supports against perpendicular movement in the opposite direction in said carrier slots.

3. A cylindrical needle carrier for a knitting machine, a series of separate needle supports detachably carried thereby in laterally spaced parallel relation to each other and respectively mounted in correspondingly laterally spaced parallel slots formed in said carrier, and a clamping band mounted in an annular groove adjacent 55 each of the opposite ends of said carrier and encircling said carrier outside said supports for retaining said supports in said slots, one of said bands including an annular rib adapted to enter a transverse groove in each support to function 60 as means for preventing longitudinal movement of the supports in the carrier slots and to function as a pivot for swinging the opposite end of a support out of its carrier groove upon release of the clamping band lying adjacent said opposite end of the support.

4. A rigid walled knitting machine needle carrier provided with laterally spaced parallel slots extending completely through one wall thereof, and a longitudinally grooved needle support removably mounted in each slot.

70. 5. A rigid walled knitting machine needle carrier provided with laterally spaced parallel slots extending completely through one wall thereof,

a longitudinally grooved needle support removably mounted in each slot, rigid means preventing said supports from displacement from said slots in one direction perpendicular to said wall, and releasable means for permitting removal of 5 said supports in an opposite direction from said slots.

6. A rigid walled knitting machine needle carrier provided with laterally spaced parallel slots extending completely through one wall thereof, 10 a longitudinally grooved needle support removably mounted in each slot, rigid means adjacent one end of each slot for preventing said supports from displacement from said slots in one direction perpendicular to said wall, and releasable 15 means for permitting removal of said supports in an opposite direction from said slots.

7. A rigid walled knitting machine needle carrier provided with laterally spaced parallel slots extending completely through one wall thereof, 20 a longitudinally grooved needle support removably mounted in each slot, rigid means extending along the length of each slot for preventing said supports from displacement from said slots in one direction perpendicular to said wall, and releasable 25 means for permitting removal of said supports in an opposite direction from said slots.

8. A rigid walled knitting machine needle carrier provided with laterally spaced parallel slots extending completely through one wall thereof, 30 a longitudinally grooved needle support removably mounted in each slot, rigid means adjacent one end of each slot for preventing said supports from displacement from said slots in one direction perpendicular to said wall, and releasable 35 means opposite said rigid means at said end of each slot for permitting removal of said supports in an opposite direction from said slots.

9. A rigid walled knitting machine needle carrier provided with laterally spaced parallel slots 40 extending completely through one wall thereof, a longitudinally grooved needle support removably mounted in each slot, rigid means adjacent one end of each slot for preventing said supports from displacement from said slots in one direction perpendicular to said wall, and releasable 45 means adjacent each of the opposite ends of each slot for permitting removal of said supports in an opposite direction from said slots.

10. A rigid walled knitting machine needle carrier provided with laterally spaced parallel slots extending completely through one wall thereof, a longitudinally grooved needle support removably mounted in each slot, rigid means preventing said supports from displacement from said 55 slots in one direction perpendicular to said wall, and releasable means extending along substantially the full length of each slot for permitting removal of said supports in an opposite direction from said slots.

11. A rigid walled knitting machine needle carrier provided with laterally spaced parallel slots extending completely through one wall thereof, a longitudinally grooved needle support removably mounted in each slot, rigid means preventing said supports from displacement from said slots in one direction perpendicular to said wall, means for preventing longitudinal movement of said supports in said slots, and releasable means for permitting removal of said supports in an opposite 70 direction from said slots.
